Primary Examiner — Katherine Glennon*Assistant Examiner* — Alison Davis(74) *Attorney, Agent, or Firm* — Andrew C. Cheng(57) **CLAIM**

The ornamental design for a data processor as shown and described.

DESCRIPTION

FIG. 1 is a front, right and top perspective view of a data processor showing our new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of an encircled portion 9 of FIG. 1;

FIG. 10 is an enlarged view of an encircled portion 10 of FIG. 1; and,

FIG. 11 is an enlarged view of an encircled portion 11 of FIG. 1.

The broken lines depict portions of the data processor that form no part of the claimed design.

1 Claim, 11 Drawing Sheets(56)
